OUTBOARD MOTOR BRACKET

Lloyd J. Harmon, New York, N. Y., assignor to
Outboard, Marine & Manufacturing Company,
Wilmington, Del., a corporation of Delaware

Application September 23, 1937, Serial No. 165,263

6 Claims. (Cl. 248—4)

This invention relates to improvements in outboard motor brackets.

It is the primary object of the invention to provide a fully adjustable false transom for use on boats of varying free-board above the water line to enable conventional outboard motors to be used in the propulsion of such boats, while rendering such motors freely tiltable about either one or both of two different horizontal axes, and providing means for maintaining the motor in tilted adjustment either while it is in position for use or for the purpose of enabling it to be lifted above the water level. This last feature is of particular advantage in the case of sailing vessels on which the motor can be manipulated with a minimum of handling from its stored position to its active position, the stored position being such as to keep the propeller out of water, thus avoiding the drag which would be occasioned by its continuance in the active position. The utility of my improved bracket is, however, not limited to the adaptation of outboard motors for use on sail boats. On the contrary, the bracket is of almost universal application and may even be used in connection with small row-boats or the like, if desired. Other objects of the invention will appear from the following disclosure.

In the drawing:

30 Figure 1 is a side elevation showing my device in use as a means of mounting an outboard motor on the stern or transom of a relatively large boat.

35 Figure 2 is an enlarged detail view of the apparatus as it appears in plan when viewed separately.

Figure 3 is a view looking aft at the false transom from the position indicated at 3—3 in Fig. 2, the adjustable bar of the device being shown 40 in section.

Like parts are identified by the same reference characters throughout the several views.

The transom plate 4 is connected, as by bolts or screws 5, to the stern 6 of the boat 7. Segment means project aft from plate 4. In the particular embodiment of the invention illustrated, the second means comprises a pair of generally semi-circular flanges 8 which are spaced from each other and provided with corresponding rows of apertures to receive adjustably the supporting bolt 9. The apertures may conveniently be arranged in sets concentrically about the axis of the pintle bolt 10 upon which the supporting bar 11 is fulcrumed for pivotal movement to and from whatever position is deter-

mined for it by the adjusting bolt 9. The adjusting bolt preferably passes beneath the bar 11, rather than through the bar, so that the bar will be free to move upwardly from the position in which it normally rests as shown in full lines 5 in Fig. 1 toward the position shown in dotted lines, or even therebeyond.

At the aft end of the bar there is an almost identical arrangement except that the plate, in this case, takes the form of a false transom 15 of a size and shape to be adapted to receive the conventional transom bracket clamp 16 of an ordinary outboard motor such as is generically designated by reference character 17. The plate 15, like plate 4, has the segment means which, 15 in the illustrated device, comprises a pair of ears 18 provided with corresponding apertures in arcuately disposed sets to receive the adjustable bolt 19. The supporting bar 11 is fulcrumed on the pintle bolt 20 which passes through the 20 two ears 18 substantially at the point about which the arcuate set of holes is concentric. In this instance also, the distribution of weight is such that the adjusting bolt is preferably used below the bar 11. 25

It will be apparent from Fig. 1 that the thrust of the propeller 21 will be exerted in a direction tending to oscillate the false transom plate 15 about the pintle bolt 20 in a counter-clockwise direction, thus maintaining the adjustable bolt 30 19 tight against the under surface of the supporting bar 11.

The thrust is likewise transmitted through the supporting bar in a direction tending to oscillate that bar in a counter-clockwise direction about its upper fulcrum on bolt 10. This thrust is absorbed by the adjusting bolt 9 during normal operation. If, however, a submerged obstacle should be encountered, the false transom plate 15 could oscillate on the pintle bolt 20 40 to permit the lower unit of the outboard motor to swing out of the water. If the clearance was inadequate, or if the shock were more nearly vertical, the bar 11, together with the entire false transom assembly, could oscillate bodily 45 toward the dotted line position in which it appears in Fig. 1.

Thus, even though the outboard motor is not equipped with a tilting feature, it is rendered tiltable by the use of the present invention. The 50 tilting not only occurs automatically as when a submerged obstacle is encountered, but it may be effected by manipulating or elevating the motor as shown in Fig. 1 and securing it in its elevated position by readjusting the bolt 9 so 55

that the motor will be supported clear of the water.

It will be apparent that by means of this invention a scow, barge, or sail boat or other craft of a size too high to be adapted to use a conventional outboard motor, can now be equipped with a conventional outboard motor which will be carried above the water line but instantly available for use and with advantages in the way of adjustment which are not present in most commercial outboard motors used without the benefit of this invention. It will also be understood that the plate 4 may be made of various shapes to fit different types of sterns and that numerous modifications may be made in the apparatus herein disclosed without altering the principle upon which it operates.

Where the outboard motor is of a well known type which in itself has sufficient provision for angularity of adjustment to maintain it vertical, the adjustable connection between the false transom plate 15 and the supporting arm 11 may be dispensed with.

I claim:

- 25 1. An outboard motor bracket comprising a pair of plates, one of which is shaped for attachment to the stern of a boat and the other of which comprises means adapted to receive an outboard motor, and a support pivotally connected with both of said plates, each of said plates having mechanism for adjustably restraining relative pivotal movement between said support and the respective plate, whereby to fix a position of said outboard motor and to transmit thrust therefrom.
- 30 2. An outboard motor bracket comprising the combination with a mounting plate provided with a transverse pintle, of a supporting arm fulcrumed on said pintle, a false transom plate having a similar pintle upon which said arm is fulcrumed, and thrust mechanism connected with the respective plates and engageable, in each instance, against the under surface of said arm, whereby adjustably to limit the angular movement of said plates respecting said arm in one direction while leaving such plates free for relative movement respecting said arm in the other direction.
- 35 3. An outboard motor bracket comprising a mounting plate having spaced ears provided with

corresponding sets of apertures, a pintle connecting said ears, an arm pivoted on said pintle and provided with an outboard motor support, and a thrust member extending through corresponding apertures of said ears beneath said pintle to receive the weight and thrust of said arm.

4. An outboard motor bracket comprising a mounting plate having spaced ears provided with corresponding sets of apertures, a pintle connecting said ears, an arm pivoted on said pintle and provided with an outboard motor support, and a thrust member extending through corresponding apertures of said ears beneath said pintle to receive the weight and thrust of said arm, said outboard motor support comprising a false transom having like ears, pintle, and thrust member, said arm being disposed between the last mentioned ears and pivoted on the last mentioned pintle in abutment with the last mentioned thrust member.

5. An outboard motor bracket comprising the combination with an arm, of a false transom pivoted to one end of the arm, a mounting plate pivoted to the other end of the arm, thrust means engageable between the false transom and one side of the arm to restrain relative movement in one direction, and a second thrust means engageable between the mounting plate and the same side of the arm to restrain relative movement in one direction, said arm being free for relative movement with respect to the false transom and the mounting plate in directions opposite to those against which it is restrained by the respective thrust means.

6. An outboard motor bracket comprising the combination with a false transom, of an arm in adjustable connection therewith, means for securing said transom against relative movement in a thrust delivering direction respecting said arm, a mounting plate having a pivotal connection with said arm and thrust means adjustably connected with the mounting plate and engageable by said arm to define a predetermined angular position thereof with respect to the mounting plate, said arm being freely movable from said thrust means in an upward direction away from said position.

LLOYD J. HARMON.
